C. C. FARMER

LOCOMOTIVE AIR TURRET

Filed Nov. 1, 1923

Fig. 1.

INVENTOR
CLYDE C. FARMER
BY *W. M. Cady*
ATTORNEY

UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMINGTON, PENNSYLVANIA, A CORPORATION OF PENNSYLVANIA.

LOCOMOTIVE AIR TURRET.

Application filed November 1, 1923. Serial No. 672,094.

To all whom it may concern:

Be it known that I, CLYDE C. FARMER, a citizen of the United States, residing at Pittsburgh, in the county of Allegheny and 5 State of Pennsylvania, have invented new and useful Improvements in Locomotive Air Turrets, of which the following is a specification.

This invention relates to fluid pressure 10 controlled apparatus, and more particularly to manually operated mechanism for controlling the fluid pressure for operating various auxiliary devices on a steam locomotive.

15 On modern steam locomotives, many accessories and parts are caused to function by the use of fluid under pressure, the supply of fluid pressure being controlled by corresponding manually operable valves located 20 in the locomotive cab or elsewhere.

Included among such accessories or parts are rail sanding devices, fire door operators, grate shakers, reverse gear operators, ash pan door controllers, bell ringers, and water 25 scoop operators.

The principal object of my invention is to provide a unity controlling mechanism for the various pneumatically operated devices on the locomotive, comprising a single 30 bracket or valve base to which all of the pneumatic control pipes lead and associated with which are the several manually operable valves by which the supply and release of fluid under pressure to and from the various pneumatically controlled devices is effected.

In the accompanying drawing; Fig. 1 is a diagrammatic view, partly in section, of a pneumatic control mechanism for a locomotive, constructed in accordance with my invention; Fig. 2 a diagram, illustrating the various operating positions of one of the manually controlled valves shown in Fig. 1; and Fig. 3 a diagram, illustrating the operating positions of the other manually controlled valves.

According to my invention, a combined pipe bracket and valve base 1 is employed to which the various pneumatic control pipes 50 connect, such as pipe 2 for operating a pneumatic rail sander associated with the front drive wheels for sanding rails ahead of the front drive wheels when the locomotive is running forward; pipe 3 for sanding the

rails at the rear drive wheels ahead of the 55 wheels when the locomotive is running forward; pipe 4 for sanding the rails at the front drive wheels when the locomotive is moving in reverse; pipe 5 for sanding the rails at the rear drive wheels when the locomotive is in reverse; pipe 6 for controlling the fluid pressure for operating the fire doors; pipe 7 the grate shakers; pipe 8 the reverse gear; pipe 9, the ash pan doors; pipe 10, the bell ringer; and pipe 11, the 65 water scoop.

Pipes 2, 3, 4, and 5 lead to a valve seat of the bracket 1 on which is mounted a rotary slide valve 12; pipes 6 and 7 to a valve seat having a rotary slide valve 13; 70 pipes 8 and 9 to a valve seat having a rotary valve 14; and pipes 10 and 11 to a valve seat having a rotary slide valve 15.

The rotary slide valves 12, 13, 14, and 15 are contained in the respective valve chambers 16, 17, 18, and 19, and are adapted to be manually operated by the respective 75 handles 20, 21, 22, and 23.

The fluid pressure supply for the various pneumatic devices may be taken from the 80 usual main reservoir 24, but in order to prevent possible depletion of pressure in the main reservoir by supply to the auxiliary devices, an additional supply reservoir 25 is provided, which is charged with fluid under 85 pressure through the operation of a governor device 26. The governor device 26 may be similar to that shown in prior Patent No. 1,131,969, of Walter V. Turner, dated March 16, 1915, by which the additional 90 reservoir is only charged from the main reservoir when the pressure in the main reservoir has been increased to a predetermined degree and below said predetermined degree, communication through 95 which fluid is supplied from the main reservoir to the additional reservoir is cut off.

The additional reservoir 25 is connected to a passage 27 in the pipe bracket 1, said passage having branch passages which lead to 100 the respective valve chambers 16, 17, 18, and 19.

The diagram shown in Fig. 2 does not represent the actual construction of the 105 rotary slide valve 12, but serves merely to illustrate the operation of the valve.

If the handle 20 is turned to position "a" as shown in Fig. 2, pipe 2 is connected to

supply pipe 27 through cavity 28 in the rotary valve 12, so that fluid under pressure is supplied to operate the sanding device for supplying sand to the rails ahead of the 5 front drive wheels as the locomotive is running ahead. In position "b" fluid is supplied only to pipe 3 connected to the sanding device for the rear drive wheels for sanding the rails ahead of said wheels when the 10 locomotive is running forward. In position "c," both pipes 2 and 3 are supplied with fluid pressure, so that the rails are sanded ahead of both the front and rear drive wheels. In position "d", fluid pressure is supplied only to pipe 4 for sanding the rails at the rear of the front drive wheels while the locomotive is running rearward. In position "e" fluid is supplied only to pipe 5 for sanding the rails at the rear of 15 the rear drive wheels while the locomotive is in reverse, and in position "f" fluid is supplied to both pipes 4 and 5.

The diagram shown in Fig. 3 serves to illustrate the operating positions of the 25 other three valves 13, 14, and 15.

For the valve 13 in position "a" fluid is supplied only to pipe 6 for operating the fire door. In position "b" fluid is supplied only to pipe 7 for operating the grate 30 shaker, and in position "c" fluid is supplied to both pipes 6 and 7 for operating simultaneously both the fire door and the grate shaker.

Employing the same diagram shown in 35 Fig. 3, the valve 14 in position "a" supplies fluid to pipe 8 for operating the reverse gear. In position "b" the valve supplies fluid only to pipe 9 for operating the ash pan

doors, and in position "c" fluid is supplied to both pipes 8 and 9 for operating the reverse gear and the ash pan doors at the same time. Similarly, with valve 15, in position "a" the bell ringer alone is operated, in position "b" the water scoop, and in position "c" both the bell ringer and the water scoop may be operated. 40 45

Having now described my invention, what I claim as new and desire to secure by Letters Patent, is:

1. In a fluid pressure control apparatus 50 for locomotives, the combination with a pipe bracket having connected thereto, pipes for sanding, for controlling the fire door, the reversing gear, and the bell ringer, of separate manually operable valves having seats on said pipe bracket, one for controlling the sand pipes, another the fire door pipe, another the reversing gear pipe, and another the bell ringer pipe. 55

2. In a fluid pressure control apparatus 60 for locomotives, the combination with a pipe bracket having connected thereto, pipes for sanding, for controlling the fire door, the grate shaker, the reversing gear, the ash pan doors, the bell ringer, and the water scoop, 65 of separate manually operable valves having seats on said pipe bracket, one for controlling the sand pipes, another for controlling the fire door and grate shaker pipes, another the reversing gear and the ash pan door pipes, and another the bell ringer and water scoop pipes. 70

In testimony whereof I have hereunto set my hand.

CLYDE C. FARMER.
